(57) **CLAIM**

The ornamental design for a robot as shown and described.

DESCRIPTION

FIG. 1 is a perspective view of a first embodiment of a robot showing my new design;

FIG. 2 is a front elevational view thereof;
FIG. 3 is a left side elevational view thereof;
FIG. 4 is a right side elevational view thereof;
FIG. 5 is a top plan view thereof;
FIG. 6 is a partially enlarged front, top, right perspective view thereof;
FIG. 7 is a partially enlarged front, right perspective view thereof;
FIG. 8 is a partially enlarged front, left perspective view thereof;
FIG. 9 is a partially enlarged front, right, bottom perspective view thereof;
FIG. 10 is a partially enlarged front elevational view thereof;
FIG. 11 is a partially enlarged left side elevational view thereof; and
FIG. 12 is a partially enlarged right side elevational view thereof.
FIG. 13 is a perspective view of a second embodiment of a robot showing my new design;
FIG. 14 is a front elevational view thereof;
FIG. 15 is a left side elevational view thereof;
FIG. 16 is a right side elevational view thereof;
FIG. 17 is a top plan view thereof;
FIG. 18 is a partially enlarged front, top, right perspective view thereof;
FIG. 19 is a partially enlarged front, right perspective view thereof;
FIG. 20 is a partially enlarged front, left perspective view thereof;
FIG. 21 is a partially enlarged front, right, bottom perspective view thereof;
FIG. 22 is a partially enlarged front elevational view thereof;
FIG. 23 is a partially enlarged left side elevational view thereof; and,
FIG. 24 is a partially enlarged right side elevational view thereof.
The dot-dash broken lines defining boundaries of the claimed design form no part of the claimed design. The light gray areas of the robot that are outside of the dot-dash broken lines form no part of the claimed design.
